UNITED STATES PATENT OFFICE.

JOHN C. DUNCAN, OF BENTON, ILLINOIS.

AUTOMATIC CAR-COUPING.

1,119,254.

Specification of Letters Patent.

Patented Dec. 1, 1914.

Application filed March 30, 1914. Serial No. 828,298.

To all whom it may concern:

Be it known that I, JOHN C. DUNCAN, a citizen of the United States, residing at Benton, in the county of Franklin and State 5 of Illinois, have invented certain new and useful Improvements in Automatic Car-Couplers; and I do declare the following to be a full, clear, and exact description of the invention, such as will enable others skilled 10 in the art to which it appertains to make and use the same.

This invention relates to new and useful improvements in car couplers and the primary object of the invention is to provide 15 an improved construction for automatically coupling two cars when the same are brought into abutting relation to one another.

A further object of the invention resides 20 in providing a construction which is such as will positively retain the cars in their coupled relation throughout the use of the device, until such time as manually released.

Still another object of the invention resides 25 in providing an improved bumper or buffer construction for use in connection with the male section of the coupler.

A still further object resides in providing a device which is simple and durable in construction, inexpensive to manufacture, and one which will be very efficient in use.

With these and other objects in view, my invention resides in the novel features of construction, combination and arrangement 35 of parts, as will be hereinafter referred to and more particularly pointed out in the specification and claims.

In the accompanying drawings forming a part of this application; Figure 1 is a side 40 elevation of a device constructed in accordance with my invention and applied to use, showing the section uncoupled; Fig. 2 is a bottom plan view thereof; Fig. 3 is a vertical longitudinal section through the device in its coupled position; Fig. 4 is a plan view thereof with parts broken away; Fig. 5 is a vertical transverse section as seen on line 5—5 of Fig. 3; Fig. 6 is a plan view of a detail of the invention; Fig. 7 is a side 45 elevation of a slightly modified form of bumper for use on this device; and Fig. 8 is a top plan view thereof.

In describing the invention I shall refer to the drawings in which similar reference 55 characters designate corresponding parts throughout the several views and in which

1 and 2 indicate, respectively, cars which are designed to be coupled one to the other, said cars employing, respectively, sections of my improved coupler. The car or truck 60 2 employs the female portion of the device, and in carrying out this idea, the draw bar 3, which is mounted on the top face of the floor of the car and extended longitudinally thereof, has the forward portion of the same 65 provided with a longitudinal slot 4. On the top face of the floor of the car 2 over the slotted end of the draw bar 3 is a housing or casing 5, designed somewhat similar to the ordinary draw head in car couplers. The 70 mouth portion 6 of this casing or substantially the draw head, has the outer face thereof beveled and said casing 5 is partially countersunk in the top face of the floor of said car 2.

As stated above, the casing or housing 5 is applied on the car 2 to extend over the forward or slotted end of the draw bar 3, the latter terminating at a point adjacent the mouth of said casing or housing. The 80 forward portion of the housing or casing 5, on each side of the mouth 6 therein, is provided with a vertical channel 7 through which are loosely disposed the arms of an inverted U-shaped bar 8. The upper face 85 of the housing or casing 5 is provided with a channel connecting the channels 7, wherein in the base of this U-shaped member 8 may be received. Pivotal carried on the base which forms the upper portion of this U- 90 shaped bar 8, is a connecting pin 9 which operates through a slot 10 in the upper portion of the housing or casing. The lower free end of this connecting pin 9 is received in the slot 4 of the draw bar 3 when 95 the U-shaped bar is in its normal position, and the forward swinging movement of said connecting pin 9 is limited by its engagement with the front wall of the slot 10 of the casing and the forward wall of the slot 4 100 in the draw bar. Said connecting pin 9 may be swung rearwardly and upwardly to some distance and is only limited in such movement by the rear wall of the slot 10 in said housing or casing 5.

The arms of the U-shaped bar 8 extend completely through channels in the floor of the car 2 and depend to a plane a short distance therebelow. The free ends of said arms are bent angularly and are pivotally 110 connected with the inner ends of a pair of fulcrumed levers 11, said levers being ful-

crumpled intermediate of their ends at points indicated as 12. The extreme outer end of the levers 11 project slightly beyond the side edges of the platform of the car 2 and 5 form foot tripping means indicated as 13, and it will be seen from this construction, that by forcing downwardly on the ends 13 of the levers 11, the U bar 8 is elevated, thereby lifting the connecting pin 9. In 10 elevating these portions of the device, the lower free end of the pin 9 is disposed to a plane above the plane of the upper edge of the mouth 6, thereby permitting an additional connecting member to be entered therethrough, as will be hereinafter and 15 more particularly set forth.

The male portion of the device applied to the car 1 consists of an elongated housing or casing 14 which is applied to the top face of 20 the floor or platform of said car over a portion of the draw bar 15 thereon. That portion of the platform or floor of the car 1 over which the casing or housing 14 extends, is slotted as shown at 16 for a purpose to be 25 hereinafter and more particularly set forth.

Mounted in bearings 17 on the under face of the car 1 and extending transversely thereof, is a rock shaft 18. Mounted about centrally of this shaft is a sleeve 19 having 30 a pair of upwardly extending spaced apart arms 20 formed thereon. These arms 20 project upwardly through the slot 16 and an additional depending arm 21 is formed on the sleeve disposed in the opposite direction 35 to the arms 20. Pivots held between the upper ends of the spaced arms 20 is a link 22 and pivotally connected to the outer end of the link 22 is a main connecting link 23. A vertical pin 24 is mounted in the end of the 40 casing or housing 14 and projects through the slotted portion of the connecting link 23 to guide the latter in its movement.

The outer end portion of the slot 16 in the base or platform of the car 1 is enlarged and 45 receives therein the main portion of a metal bumper 25. This bumper is held in place by means of a transversely extending bar 26 secured to the under face of the base or platform of the car, and the rear end of this 50 bumper is provided with a depending and rearwardly inclined arm 27. This arm 27 is bifurcated at its outer end and has pivotal connection with a link 28 which also pivotally connects with the depending arm or 55 projection 21 on the sleeve 19.

It will thus be seen that upon the actuation of the link 23, the bumper 25 will be actuated or vice versa. This bumper is adapted to normally project beyond the end of the 60 car, however, and in order to provide for this, weights 29 are provided on arms projecting rearwardly from the ends of the rock shaft 18. In view of the fact that the bumper is normally thrust somewhat beyond 65 the end of the car, it will be seen that the

link 23 will be drawn inwardly with respect to the housing or cover 14, and when the two cars are brought in abutting relation, the bumper being forced inwardly, will rock the shaft 18, thereby causing the link 23 to be 70 extended and properly engaged with the connecting pin in the opposite section of the coupler.

In Figs. 7 and 8, I have shown a slightly modified form of bumper. In the form of 75 bumper described the same is solid throughout its length and of considerable thickness. In this form, however, a body 30 of plate-like design is provided, the same tapering rearwardly as shown at 31 and the outer end 30 of the body is bent upwardly and angularly as shown at 32 to provide the engaging or abutting end of said bumper. The upper angular portion thereof is, however, provided with a space or offset indicated as 33 85 to accommodate the draw bar therethrough. The extreme inner end of this bumper is bent somewhat downwardly and bifurcated as indicated at 34, whereby the same may be readily engaged with a link to connect the 90 same with the operating portions of the device. This form of bumper may be readily substituted for the form of bumper shown in connection with the first mentioned form 95 of coupler.

In operation, assuming that the sections of the coupler are properly applied to the respective cars, said cars are brought together to abut one another and the bumper 25 of the car 1 will contact with the end of the car 2. 100 Such contact will, as explained above, cause the shaft 18 to be rocked and dispose the connecting link 23 outwardly. The coupling portions of the device are disposed in the same longitudinal plane, so that this link, 105 when so disposed outwardly with respect to its casing, will be received in the mouth 6 of the casing or housing 5 on the other car. The disposition of the link 23 through the mouth will force the connecting pin 10 rearwardly and upwardly and in being so disposed, said pin is caused to engage the connecting link 23, so that the sections of the coupler will be automatically engaged one with the other. The cars are then coupled 110 and proceed in travel. When it is desired to uncouple cars, it is only necessary for the operator to place his foot upon the one end 13 of the lever 11, thereby causing the member 8 with the connecting pin thereon to be elevated. This disengages the connecting pin 115 from the link and will enable the car carrying the link to proceed without the car carrying the pin.

From the foregoing it will be seen that I 125 have provided a simple, inexpensive and efficient means for carrying out the objects of the invention, and while I have particularly described the elements best adapted to perform the functions set forth, it is obvious 130

that various changes in form, proportion, and in the minor details of construction may be resorted to, within the scope of the appended claims, without departing from the spirit or sacrificing any of the principles of the invention.

Having thus described my invention, what I claim is:

1. In a car coupler, a car bottom slotted 10 at its end, a shaft extending transversely of said bottom and mounted for oscillation thereon, a crank arm carried on said shaft and projecting through said slot above said bottom, another crank arm carried by said 15 shaft and extending below said bottom, a bumper mounted for sliding movement in said slot and having pivotal connection with the lower crank arm, a connecting link engaged with the upper crank arm and adapt- 20 ed to project beyond the end of the car bottom and means in connection with said shaft whereby to normally dispose said bumper to its extended position with respect to the car bottom.
2. In a car coupler, a car bottom pro- 25 vided with a longitudinal slot at the end thereof, a transverse shaft mounted for os- cillation on the under face of said bottom, a crank arm provided centrally on said shaft 30 and projecting through said slot to a point above said bottom, another crank arm car- 35 ried by said shaft and extending below said bottom, a bumper mounted for sliding move- 40 ment in the slotted end of said bottom and having a depending inner end portion there- 45 on, means for pivotally connecting the last mentioned portion of the bumper with the lower crank arm, a connecting link having engagement with the upper crank arm above the top face of said bottom, said link being 50 adapted to project beyond the end of said car bottom, and weighted means in connec- 55 tion with said shaft for normally oscillating the latter to a predetermined position where- 60 by to dispose said bumper to its extended 65 position with respect to the car bottom.
3. In a car coupler, a car bottom slotted 70 at the end thereof, a shaft mounted for os- cillation on the under face of said bottom 75 and extending transversely of said slotted portion, crank arms carried centrally on 80 said shaft and extending in opposite direc- 85 tions, the one crank arm extending upwardly through the slot in said car bottom 90 to a plane above the top face of said bottom, 95 a bumper mounted for sliding movement in the outer slotted portion of the car bottom, the inner end of said bumper being disposed inwardly and downwardly, linking means between the other of said crank arms and the inner extremity of said bumper, a connect- 100 ing link pivotally engaged with the upper extremity of the first mentioned crank arm and adapted to extend beyond the end of said car bottom, a housing mounted on the upper face of said car bottom and receiving said connecting link and the first mentioned crank arm therein, and weighted means in connection with said shaft to rock the same to a position for normally dispos- 105 ing said bumper in its extended position with respect to the car bottom.
4. In a car coupler, a car bottom slotted at the end thereof, a shaft mounted for os- cillation on the under face of said bottom and extending transversely of the slot therein, a pair of crank arms carried on said shaft and extending in opposite directions, the one crank arm being extended through the slotted portion of the bottom and pro- 110 jected to a plane above the top face of said bottom, a bumper mounted in the outer slotted portion of the bottom and having a downwardly and rearwardly inclined pro- 115 jection on the inner end thereof, linking means between said projection and the other of said crank arms, a connecting link having pivotal connection with the upper extremity of the first mentioned crank arm and extend- 120 ing longitudinally of the car bottom to project beyond the end thereof, a housing mounted on the top face of said car bottom to inclose said first mentioned crank arm and receiving said connecting link therein, means in the housing for guiding said connect- 125 ing link in its longitudinal movement, and weighted means in connection with the shaft for disposing the latter to a position whereby said bumper will be normally dis- 130 posed in its extended position with respect to the car bottom.

In testimony whereof I have hereunto set my hand in presence of two subscribing wit- 135 nesses.

JOHN C. DUNCAN.
